FILLED CAN JETTING MECHANISM

Ronald E. J. Nordquist, Maplewood, N. J., assignor
to American Can Company, New York, N. Y., a
corporation of New Jersey

Application September 4, 1937, Serial No. 162,532

28 Claims. (Cl. 226—69)

The present invention relates to a jetting mechanism for liquid filling machines or the like and has particular reference to jetting a fluid into a liquid filled container so that the contents of the container will be agitated sufficiently to boil up or foam over and to temporarily fill the head space in the container thereby excluding the air preparatory to sealing the container.

An object of the invention is the provision of a mechanism for jetting inert gas or gas charged liquid into a liquid filled container and below the surface level so that the adjacent surface liquid is agitated enough to produce a foam which boils up and fills the head space of the container thus excluding the air preparatory to sealing.

Another object is the provision of a jetting mechanism of this character having a plurality of jetting elements operating in time with the travel of a continuously moving procession of liquid filled containers for introducing into each container a charge of fluid which effects a foaming up of the liquid so that air in the head space of the container will be excluded.

Another object is the provision of such a jetting mechanism wherein the pressure of the gas jetted into the filled containers is controlled so that the liquid will not be agitated too much and so that a uniform fine creamy foam is produced on the surface of the liquid.

Still another object is the provision of a jetting mechanism wherein the gas introducing element is cleaned out by flushing with filtered water after each jetting operation and the water is then expelled and replaced by filling gas so that the element will be ready for immediate action in a subsequent jetting operation.

Numerous other objects and advantages of the invention will be apparent as it is better understood from the following description, which, taken in connection with the accompanying drawings, discloses a preferred embodiment thereof.

Referring to the drawings:

Figure 1 is a perspective view with parts broken away, of a jetting mechanism embodying the instant invention, the view also including a wiring diagram of the electric apparatus used with the mechanism;

Fig. 2 is an enlarged section taken substantially along a horizontal plane indicated by the lines 2—2 in Fig. 1;

Fig. 3 is a sectional view taken substantially along the broken line 3—3 in Fig. 2;

Fig. 4 is a horizontal section taken substantially along the line 4—4 in Fig. 3; and

Fig. 5 is an enlarged vertical section taken substantially along the line 5—5 in Fig. 4.

As a preferred embodiment of the instant invention the drawings disclose an apparatus in which uncovered containers A filled with a liquid are moved in a continuous procession past a jetting device B (Fig. 1). The containers may contain beer, as one example of a suitable liquid to be jetted, although the invention is equally well adapted to any other jettatable liquid.

As a container A passes the jetting device B a charge of fluid, preferably carbon dioxide gas if the liquid is beer, is introduced into the liquid (i. e., the beer) below its surface level. The charge of carbon dioxide agitates a portion of the beer near its surface effecting a foaming up in a uniform creamy consistency. The foam fills the head space in the container and overflows thereby excluding the air. While the container is in this air freed condition it is passed on to a suitable place of deposit for closing and sealing with a cover.

The filled containers A to be jetted are introduced in timed order into the apparatus in any suitable manner, as for example, by way of a runway 11 (Fig. 1) having inner and outer guide rails 12, 13. The apparatus end of the runway is supported on a ledge 14 formed on a main frame 15 which supports the various parts of the mechanism. If desired the runway may lead directly from a container filling machine or the like or the runway may be dispensed with entirely and the jetting device B directly incorporated as a part of such a container filling machine.

The filled containers are propelled through the mechanism by a horizontal star wheel 18 (see also Figs. 2 and 3) which is disposed just above the top of the main frame 15. The star wheel is provided with pockets 19 for retarding the cans in spaced and timed order. The star wheel is mounted on a vertical shaft 21 which is carried in a bearing 22 formed in the frame 15 and also in a bearing 23 formed in a head plate 24 disposed above the star wheel and secured by bolts 25 to the frame 15.

Star wheel shaft 21 is continuously rotated by a spur gear 31 which is carried on the shaft just under the star wheel 18. The gear meshes with a pinion 32 carried on a drive shaft 33. The drive shaft may be the motor shaft of an electric motor 38 (indicated in the wiring diagram in Fig. 1) or may be a part of suitable driving means connecting with such a motor.

Containers propelled by the rotating star wheel 18 are supported on top of the main frame 15.

These containers are guided by a curved peripheral portion of the head plate 24 and also by a curved extension 36 of the runway outer guide rail 13. The extension 36 is secured to the main frame 15 by a bracket 37.

The jetting device B includes an annular stationary cam 41 (Fig. 3) which is bolted on top of the head plate 24 adjacent the path of travel of the containers A. The cam is provided with a cam groove 42. The inner wall section of the cam is shouldered as at 43 for supporting a rotatable turret 45.

Turret 45 extends over the top of the cam 41 and is provided with spaced pairs of depending lugs 46 (see also Figs. 1 and 2) which carry a plurality of bell crank levers 47. Each lever is carried on a pivot pin 48 secured in a pair of the lugs 46. One leg of the bell crank lever extends toward the cam 41 and carries a cam roller 49 which operates in the cam groove 42. The other leg of the bell crank lever projects upwardly and is cut away to form springlike side wings 51 for clamping around and tightly holding a jetting element or nozzle 52. There is one of these nozzles for each lever 47, there being six nozzles and six levers shown in the drawings although any number may be supplied in accordance with the desired design of the apparatus.

The turret 45 is continuously rotated by a vertical worm shaft 55 the lower end of which is journaled in a depending bearing 56 formed on a housing 57. The upper end of the shaft is journaled in a bearing formed in a cover plate 58 seated on top of the housing. The housing is secured to the side of a short column 59 which is fastened to the head plate 24 and which surrounds the upper end of the star wheel shaft 21. Within the housing 57 the shaft 55 carries a worm wheel 62 which meshes with a worm 63 mounted on one end of a horizontal cross shaft 64. This cross shaft is carried in a bearing 65 formed in the housing 57.

The opposite end of the shaft 64 carries a bevel gear 66 which meshes with a similar gear 67 mounted within the column 59 on a stud 68. Bevel gear 67 is formed integrally with a spur gear 68 which meshes with a gear 71 mounted on the upper end of the star wheel shaft 21. Hence as the star wheel shaft 21 rotates the star wheel 18 for moving the containers past the jetting devices B, it also rotates the turret 45 and thus moves the nozzles 52 carried thereon in time with the movement of the containers.

As a can A propelled by the star wheel 18 approaches the jetting devices, a nozzle 52 sweeps into position over the top of the can and travels with it through a short arc of travel. During this travel the cam 41 tilts the bell crank lever 47 carrying the nozzle and thereby dips the outer end of the nozzle into the beer within the container as shown in Fig. 3. The discharge end of the nozzle extends slightly below the surface of the beer. It is while the nozzle is in this position with its discharge end immersed in the beer that the charge of carbon dioxide gas is jetted into the beer.

The jetting of the gas into the beer is controlled by valve instrumentalities which include an upper or stationary valve member 75 (Figs. 3, 4 and 5) and a lower or rotatable valve member 76. The stationary valve member 75 is annular in shape and surrounds the worm shaft bearing 56 adjacent the housing 57. Pins 78

secured in the housing and in the valve member hold the latter stationary.

The rotating valve member 76 is cup shape and is disposed below the stationary valve member 75. The upper portion of the rotating valve member surrounds the worm shaft bearing 56 while the lower portion is keyed to the rotating worm shaft 55. Hence the rotating valve member revolves with the turret 45 and the nozzles 52 carried thereon. A compression spring 79 located in an annular recess 81 in the turret 45 presses the rotating valve member tightly against the bottom surface of the stationary valve member for preventing leakage between the engaging surfaces of the members.

The lower or rotating valve member 76 is provided with a plurality of receiving ports 83 which communicate with the top or valve engaging surface of the member. Each port also communicates with a nipple 84 which is secured in the side of the valve. There is one of these ports and one of these nipples for each jetter nozzle 52, the nozzle being connected with its nipple by a tube 85. A notch 86 is formed in one of the side wings 51 of the nozzle lever 47 for clearance of the tube at its nozzle end. One of the turret lugs 46 of each pair is also cut away as at 87 to provide clearance for the tube.

The upper or stationary valve member 75 is also provided with collecting ports for cooperation with the receiving ports 83 of the rotating valve member and these communicate with the bottom or valve engaging surface of the member and also communicate with nipples 89 which are secured in the side of the valve member. These collecting ports in valve member 75 include a low pressure gas collecting port 91 (Fig. 4), a water collecting port 92, and a high pressure gas collecting port 93.

40 The low pressure gas port 91 is connected by a tube 95 to a commercial pressure reducer 96 of suitable construction which may be mounted on a shelf section 97 of the short column 59. The pressure reducer is connected into a gas pipe line 45 98 which includes a main shut-off valve 99, a bypass 101 around the shut-off valve, and a gas filter 102. The bypass is provided with a separate or auxiliary shut-off valve 103. When the 50 valve is kept closed. The pipe line 98 leads to any suitable source of jetting fluid which in the present description will be carbon dioxide preferably having a pressure of between 15 and 20 pounds. The reducer lowers this pressure to 55 between 4 and 7 pounds for use in the jetting operation.

The main shut-off valve 99 is operated by an actuating solenoid 105 which is connected in circuit with the driving motor 35 of the apparatus 60 (see wiring diagram Fig. 1). This circuit also includes a wire 106 connecting with one terminal of the solenoid coil, a hand switch 107, wire 108, a suitable source of power such as a generator 109, wire 111, motor 35, and return wire 112 which connects with the opposite terminal of the solenoid coil.

Closing of hand switch 107 completes the circuit and permits electric energy from generator 70 109 to pass through the system. This energy actuates the motor for operating the machine and simultaneously energizes the solenoid 105. The energized solenoid opens the main shut-off valve 99 and permits filtered gas to flow through the pipe line 98 into the port 91 of the stationary valve member 75.

If the motor 35 stops as by failure of current or by intention, as by opening the switch 107, the solenoid is deenergized and the main shut-off valve 89 closes. This cuts off the supply of gas. For testing the apparatus when the motor is stopped or the current is off, gas may be introduced into the valve member 75 by way of the by-pass 101. This is effected by opening the auxiliary valve 103.

When a nozzle 52 is in jetting position in a container as hereinbefore described, its corresponding port 83 in the rotating valve member 76 is in alignment with the low pressure gas port 91 of the stationary valve member 75. Hence filtered gas from the pipe line 98 passes through the valve ports 91, 83, tube 85, and nozzle 52 into the beer in the container for producing the foam hereinbefore mentioned. This flow of gas is only momentary and continues only until the rotating valve member 76 moves the operating port 83 out of register with the port 91 in the stationary valve member 75.

When the ports 83, 91 are out of register the nozzle 52 is lifted out of the container by the cam 41. The jetted container passes on to be covered and sealed and the next container in the line is brought into position for jetting by the following nozzle. Similarly the raised nozzle 52 is carried around toward the back of the mechanism and the next nozzle moves into place to jet the next positioned container.

After a jetting operation the nozzle is interiorly flushed with water to clean it free from beer which would otherwise adhere to the nozzle port at its discharge end which was dipped into the container. This flushing is effected by the corresponding nozzle port 83 of the rotating valve member 76 coming into register with the water port 92 of the stationary valve member 75.

The water port 92 is connected by a tube 115 to a water pipe line 116 which is supported in the shelf section 97 of the short column 59. The water pipe line includes a pressure reducer 118, a hand operated cut-off cock 119, and a water filter 121. The pipe line leads from any suitable source of water supply.

During normal operation of the apparatus the cock 119 is open, hence when the ports 83, 92 are brought into register filtered water (reduced to a pressure of preferably one pound) passes through the ports, the nozzle tube 85 and the nozzle 52. The used water flowing out of the nozzle discharges into a cup 125 (Figs. 1, 2 and 3) and is conveyed by a waste pipe 126 to any suitable place of deposit.

Water is expelled from a nozzle 52 after the flushing action by a blast of gas at high pressure. For this purpose the rotating valve member 76 brings the port 83 corresponding to the proper nozzle 52 into register with the high pressure gas port 83 of the stationary valve member 75.

Port 83 is connected by a tube 128 to a similar tube 129 which is supported in the shelf section 97 of the short column 59. Tube 129 connects directly with the gas pipe line 98 at a place between the main shut-off valve 89 and the pressure reducer 98. Hence the reducer is cut out and filtered gas at high pressure is passed directly from the main shut-off valve into the valve port 83. This high pressure gas shoots through the ports 83, 83, nozzle tube 85 and nozzle 52, blowing out all water left in the nozzle.

After this water expelling operation on the nozzle the rotating valve member 76 cuts off

communication between the ports 83, 93 and the nozzle moves on for another jetting operation. The carbon dioxide gas used in the expelling operation remains in the nozzle which is thus conditioned for immediate action at the beginning of the next jetting operation.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A jetting mechanism for a container filling machine or the like, comprising in combination: means for propelling uncovered liquid filled containers along a predetermined path of travel, a jetting element bodily movable with a said container for a portion of its travel and adapted to be projected into said propelled container below the liquid level therein for introducing a charge of fluid into the liquid below its surface which effects a foaming up of the liquid into the head space of the container for excluding the air preparatory to covering and sealing the container, means for projecting said jetting element into said liquid filled container, and means for flushing out said jetting element after the jetting operation.

2. A jetting mechanism for a container filling machine or the like, comprising in combination: a fluid jetting element, means for bodily moving said element in a horizontal path of travel, means for inserting said jetting element into an uncovered liquid filled container below the liquid level therein, devices for directing a predetermined charge of fluid through said inserted jetting element and into said liquid which effects a foaming up of the liquid into the head space of the container for excluding the air preparatory to covering and sealing the container, and means for flushing out said jetting element after the jetting operation.

3. A jetting mechanism for a container filling machine or the like, comprising in combination: means for propelling uncovered liquid filled containers in a continuous procession along a predetermined path of travel, a plurality of jetting elements bodily movable in registry with said containers for a portion of their path of travel, said elements being adapted to be projected individually into said propelled containers below the liquid level therein for introducing a charge of jetting fluid into the liquid below its surface which effects a foaming up of the liquid into the head spaces of the containers for excluding the air preparatory to covering and sealing the containers, means for projecting said jetting elements into said liquid filled containers, and means for flushing out said jetting element after the jetting operation.

4. A jetting mechanism for a container filling machine or the like, comprising in combination: a fluid jetting element, means for bodily moving said element in a horizontal path of travel, means for inserting and for removing said jetting element into and out of an uncovered liquid filled container below the liquid level therein, devices for directing a predetermined charge of fluid through said jetting element and into said liquid when the jetting element is in inserted position,

5. A jetting mechanism for a container filling machine or the like, comprising in combination: means for propelling uncovered liquid filled containers along a predetermined path of travel, a jetting element bodily movable with a said container for a portion of its travel and adapted to be projected into said propelled container below the liquid level therein for introducing a charge of fluid into the liquid below its surface which effects a foaming up of the liquid into the head space of the container for excluding the air preparatory to covering and sealing the container, means for projecting said jetting element into said liquid filled container, and means for flushing out said jetting element after the jetting operation.

6. A jetting mechanism for a container filling machine or the like, comprising in combination: a fluid jetting element, means for bodily moving said element in a horizontal path of travel, means for inserting and for removing said jetting element into and out of an uncovered liquid filled container below the liquid level therein, devices for directing a predetermined charge of fluid through said jetting element and into said liquid when the jetting element is in inserted position,

7. A jetting mechanism for a container filling machine or the like, comprising in combination: a fluid jetting element, means for bodily moving said element in a horizontal path of travel, means for inserting and for removing said jetting element into and out of an uncovered liquid filled container below the liquid level therein, devices for directing a predetermined charge of fluid through said jetting element and into said liquid when the jetting element is in inserted position,

8. A jetting mechanism for a container filling machine or the like, comprising in combination: a fluid jetting element, means for bodily moving said element in a horizontal path of travel, means for inserting and for removing said jetting element into and out of an uncovered liquid filled container below the liquid level therein, devices for directing a predetermined charge of fluid through said jetting element and into said liquid when the jetting element is in inserted position,

means for flushing out and cleaning said jetting element when the latter is removed from the container, and means moving in timed relation with the movement of said jetting element for controlling the operation of said flushing and cleaning means.

5. A jetting mechanism for a container filling machine or the like, comprising in combination, a fluid jetting element, means for bodily moving said element in a horizontal path of travel, means for inserting and for removing said jetting element into and out of an uncovered liquid filled container below the liquid level therein, devices for directing a predetermined charge of fluid through said jetting element and into said liquid when the jetting element is in inserted position, means for flushing out and cleaning said jetting element with water when said element is removed from the liquid within said container, means moving in timed relation with the movement of said jetting element for controlling the operation of said flushing and cleaning means, and means disposed in the path of travel of said jetting element for receiving and carrying away the waste water therefrom.

6. A jetting mechanism for a container filling machine or the like, comprising in combination, a fluid jetting element, means for inserting and for removing said jetting element into and out of the liquid of an uncovered liquid filled container, devices for directing a predetermined charge of fluid through said jetting element and into said liquid when the jetting element is inserted within the container, and means for blowing out said jetting element after a jetting operation when the element is withdrawn from the container and for refilling said element with said fluid to facilitate immediate jetting action on a subsequent container.

7. A jetting mechanism for a container filling machine or the like, comprising in combination, a fluid jetting element, means for inserting and for removing said jetting element into and out of the liquid of an uncovered liquid filled container, devices for directing a predetermined charge of fluid through said jetting element and into said liquid when the jetting element is inserted within the container, means for water flushing and cleaning said jetting element when the latter is removed from the container, and means for expelling water from said jetting element after cleaning.

8. A jetting mechanism for a container filling machine or the like, comprising in combination, a fluid jetting element, means for inserting and for removing said jetting element into and out of the liquid of an uncovered liquid filled container, devices for directing a predetermined charge of jetting fluid through said jetting element and into said liquid when the jetting element is inserted within the container, means for water flushing and cleaning said jetting element when the latter is removed from the container, and jetting fluid means for blowing out the water from said jetting element after cleaning and for filling said element with said fluid for immediate jetting action on a subsequent container.

9. A jetting mechanism for a container filling machine or the like, comprising in combination, a fluid jetting element, means for inserting into and for removing said jetting element from the liquid of an uncovered liquid filled container, devices for directing a predetermined charge of fluid through said jetting element and into said

liquid when the jetting element is inserted within the container, means for water flushing and cleaning said jetting element when the latter is removed from the container, and devices for controlling the pressure of the jetting fluid and also of the flushing water.

10. A jetting mechanism for a container filling machine or the like, comprising in combination, a fluid jetting element, means for inserting into and for removing said jetting element from the liquid of an uncovered liquid filled container, devices for directing a predetermined charge of fluid at a low pressure through said jetting element and into said liquid when the jetting element is in inserted position within the container, means for flushing out and cleaning said jetting element with water at a low pressure when the element is withdrawn from the container, devices for directing a blast of the jetting fluid at a high pressure through said jetting element for expelling waste water from the element after cleaning, and means for controlling the pressures of said fluid and of said water.

11. A jetting mechanism for a container filling machine or the like, comprising in combination, a fluid jetting element, means for bodily moving said element in a horizontal path of travel, means for inserting and for removing said jetting element into and out of an uncovered liquid filled container below the liquid level therein, devices for directing a predetermined charge of jetting fluid through said jetting element and into said liquid when the jetting element is in inserted position within the container, means for water flushing and cleaning said jetting element when the latter is removed from the container, means moving in timed relation with the movement of said jetting element for controlling the operation of said flushing and cleaning means, and means associated with said fluid directing devices and said flushing and cleaning means respectively for filtering the jetting fluid and also the water before use.

12. A jetting mechanism for a container filling machine or the like, comprising in combination, means for advancing uncovered liquid filled containers through the mechanism, a fluid jetting element bodily movable in a horizontal path with a said container for a portion of its travel, means for moving said jetting element in registry with a said container during the advancement of the latter, means for projecting said jetting element into an uncovered liquid filled container below the liquid level therein, devices for directing a predetermined charge of fluid from a suitable source of supply through said projected jetting element and into said liquid to jet the same and to sweep out air from the head space of the container, actuating devices for said container advancing means, and means included in an electrical circuit and co-operating with said actuating devices for cutting off the supply of fluid when said container advancing means stop operating.

13. A jetting mechanism for a container filling machine or the like, comprising in combination, means for advancing uncovered liquid filled containers through the mechanism, a fluid jetting element, means for inserting said jetting element into the liquid of an uncovered liquid filled container, devices for directing a predetermined charge of fluid from a suitable source of supply through said inserted jetting element and into said liquid to effect a foaming up of the liquid into the head space of the container to

exclude the air therefrom, actuating devices for said container advancing means, means co-operating with said actuating devices for cutting off the supply of fluid when said conveyor advancing means stops operating, and devices for by-passing the fluid and bringing it into said jetting element for testing purposes.

14. A jetting mechanism for a container filling machine or the like, comprising in combination, means for conveying a jetting gas from a gas supply, a stationary valve member connected with said gas conveying means and having a gas collecting port, a valve member rotatable on a vertical axis having a receiving port adapted to be brought into register with said stationary valve port, a jetting element connected with the rotatable valve receiving port for dispensing the gas received through said registered collecting port, means for bodily moving said jetting element in a horizontal path of travel and means for projecting said jetting element in a vertical direction into a liquid filled container beneath the liquid level therein and while said jetting element is being bodily moved in its horizontal path of travel, whereby to introduce a charge of the gas into the liquid to effect a foaming up thereof into the head space of the container so that the air will be excluded therefrom.

15. A jetting mechanism for a container filling machine or the like, comprising in combination, a pipe line for conveying a jetting gas from a suitable supply of such gas, devices including a gas filter, a shut-off valve and a gas pressure reducer located in said pipe line, a stationary valve member connected with the discharge end of said pipe line and having a gas collecting port for filtered reduced pressure gas, a rotatable valve member having a receiving port adapted upon rotation of said rotatable valve member to be brought into register with said gas collecting port, a jetting element connected with said receiving port of said rotatable valve member for dispensing the filtered and pressure reduced gas received through said registered ports, said jetting element being insertable into a liquid filled container to effect said dispensing of said gas, an electric motor for revolving said rotatable valve member, and a solenoid having electrical connection with said electric motor and also having actuating connection with said shut-off valve for stopping the flow of gas through the pipe line when said electric motor stops.

16. A jetting mechanism for a container filling machine or the like, comprising in combination, a pipe line for conveying a jetting gas from a gas supply, devices including a shut-off valve and a gas pressure reducer located in said pipe line, a stationary valve member connected with the discharge end of said pipe line and having a reduced pressure gas collecting port, a rotatable valve member having a receiving port adapted to be brought into register with said gas collecting port, a jetting element connected with said rotatable valve receiving port for dispensing the pressure reduced gas when said valve ports are in register, said jetting element being insertable into a liquid filled container and when in inserted position introducing a charge of the pressure reduced gas into the liquid, an electric motor for revolving said rotatable valve member, a solenoid electrically connected with said electric motor and also having actuating connection with said shut-off valve for controlling the flow of gas through the pipe line, and means for admitting gas into the gas collecting port of said

stationary valve member for testing purposes when the electric motor is stopped and the shut-off valve is closed.

17. A jetting mechanism for a container filling machine or the like, comprising in combination, means for conveying a jetting gas from a gas supply, a gas pressure reducer for reducing the pressure of said gas as received from said supply, a stationary valve member having a low pressure gas collecting port and a high pressure gas collecting port, a rotatable valve member cooperating with said stationary valve member and having a receiving port, a jetting element connected with the receiving port of said rotatable valve member and insertable into a liquid filled container, and means for revolving said rotatable valve member to bring its receiving port first into register with said low pressure gas collecting port for directing a charge of gas at a reduced pressure through said jetting element and into the liquid of said liquid filled container and secondly to bring said receiving port into register with said high pressure gas collecting port after a jetting operation for directing a blast of the high pressure gas through the jetting element to blow out the interior of the latter.

18. A jetting mechanism for a container filling machine or the like, comprising in combination, a gas pipe line for conveying a jetting gas from a gas supply, a water pipe line including a water filter for conveying cleansing water from a water supply, a stationary valve member having a gas collecting port connected with said gas pipe line and also having a water collecting port connected with said water pipe line, a rotatable valve member rotatable on a vertical axis cooperating with said stationary valve member and having a receiving port, a jetting element connected with the receiving port of said rotatable valve member and adapted to be inserted into a liquid filled container beneath the liquid level therein, means for bodily moving said jetting element in a horizontal path of travel, and means for revolving said rotatable valve member to first bring its receiving port into registry with said gas collecting port for directing a charge of gas through said jetting element and into the liquid of the liquid filled container and secondly to bring said receiving port into registry with the water collecting port of the stationary valve member after a jetting operation for directing a charge of the filtered water through the jetting element for flushing and cleaning out the interior of the same.

19. A jetting mechanism for a container filling machine or the like, comprising in combination, a rotatable turret, means for propelling uncovered liquid filled containers in a continuous procession adjacent said turret, a plurality of jetting elements carried by said turret, means for rotating said turret in time with the travel of said advancing containers whereby a said jetting element is aligned with a said passing container, means for moving said aligned jetting element relative to said turret to insert its discharge end into the liquid of its aligned container, valve means for first connecting said inserted jetting element with a source of jetting fluid to jet the liquid within and sweep out air from the head space of said filled container and secondly for connecting said jetting element with a source of cleaning liquid after it is moved away from said inserted position to clean out the same.

20. Apparatus for the packaging of a readily foaming beverage in containers, said apparatus including means to move a series of filled but open containers, a gas discharge nozzle disposed above the path of movement of said containers, means to lower the nozzle as a filled container comes therebeneath and to elevate the same preparatory to movement of another container therebeneath, said last named means producing a downward movement of the nozzle which is adequate to bring the gas discharging tip of the nozzle beneath the surface of the beverage in the container, in order to cause agitation and foaming of the beverage.

21. In the packaging of a readily foaming beverage in containers, the method which includes filling the container with the beverage, and immediately prior to sealing the container discharging a jet of gas into the beverage at a point beneath the surface thereof in order to cause agitation and foaming of the beverage, and thereby displacing from the container any air at the top of the container above the beverage, and immediately thereafter closing the container.

22. The method of packaging gas containing beverages, which comprises substantially filling a container with the beverage in an atmosphere containing air so that the head space in the container above the liquid will contain air, conveying said filled container to a jetting station and injecting a fluid under pressure from a nozzle submerged in the liquid to thereby liberate some of said gas from the liquid and substantially expell the air from said head space.

23. A mechanism for creating foam in a liquid confined in a container which has a head space of air above said liquid, which comprises means for conveying a said container, a jetting device for fluid under pressure movable above said conveying means, and means for moving said device relative to said container to immerse said device in said liquid and jet said fluid into said liquid to create sufficient foam to drive the air out of said head space.

24. A mechanism for creating foam in a liquid confined in a container which has a head space of air above said liquid, which comprises means for conveying a said container, a jetting device for fluid under pressure movable above said conveying means, and cam actuated means for moving said device relative to said container to im-

merse said device in said liquid and jet said fluid into said liquid to create sufficient foam to drive the air out of said head space.

25. In apparatus for packaging gas containing beverages, means for supporting a container substantially filled with a gas containing beverage with a head space of air above the level of said beverage, a fluid jetting device, means to relatively move the said jetting device and supporting means so that the jetting device is submerged in the beverage and jets fluid thereinto beneath the surface thereof, a source of jetting fluid, and a flexible conduit connecting said source with said device, whereby foam is created to displace the air in said head space.

26. Apparatus for the packaging of beer in containers, said apparatus including means to move a series of filled but open containers, a gas discharge nozzle disposed above the path of movement of said containers, a valve for controlling the discharge of gas from said nozzle, means to lower the nozzle as a filled container comes therebeneath and to elevate the same preparatory to movement of another container therebeneath, said last named means producing a downward movement of the nozzle which is adequate to bring the gas discharging tip of the nozzle beneath the surface of the beer in the container.

27. In apparatus for packaging gas containing beverages, means for supporting a container substantially filled with a gas containing beverage, the top container space containing air above the beverage liquid, a gas jetting device, and means to relatively move the said jetting device and supporting means so that the jetting device is submerged in the liquid and jets gas into the liquid beneath the surface thereof, thereby causing gas to rise from the liquid and displace the said air at the top container space above the liquid.

28. The method of packaging gas containing beverages comprising, substantially filling a container with the beverage in an atmosphere containing air so that the top container space above the beverage liquid will contain air, and injecting a gaseous medium under pressure from a nozzle submerged in the liquid to thereby cause gas to rise from the liquid and displace the said air at the top container space above the liquid, and thereafter closing the container.
